UNITED STATES PATENT OFFICE

116,963

DESIGN FOR A FLACON

John A. Oya, Honolulu, Territory of Hawaii

Application June 19, 1939, Serial No. 85,546

Term of patent 7 years

To all whom it may concern:

Be it known that I, John A. Oya, a citizen of the United States of America and a resident of Honolulu, Hawaii, have invented a new, original, and ornamental Design for a Flacon, of which the following is a specification, reference being had to the accompanying drawing, forming part thereof.

In the drawing, Figure 1 is a plan view of a flacon, showing my new design; Figure 2 is a front view; and Figure 3 is a side view of same. The rear of the flacon is similar in appearance to the front view thereof.

I claim:

The ornamental design for a flacon, as shown and described.

JOHN A. OYA.
